UNITED STATES PATENT OFFICE.

SIDNEY GERNSBACK, OF NEW YORK, N. Y.

TELEPHONE RECEIVER.

Application filed May 12, 1923. Serial No. 638,645.

This invention relates to telephone receivers, and more particularly to an adjustable receiver for radio phones.

An object of the invention is to provide 5 a receiver in which the distance between the pole piece and the diaphragm may be adjusted.

A further object is the provision of adjusting means for moderate priced receivers.

In the accompanying drawings, I have shown one embodiment of the invention. In this showing:

Figure 1 is a perspective view of the receiver,

Figure 2 is a central vertical sectional view showing the pole piece arranged relatively close to the diaphragm,

Figure 3 is a similar view showing the 20 pole piece adjusted at a distance from the diaphragm, and,

Figure 4 is a transverse sectional view on line 4—4 of Figure 2.

Referring to the drawings, the reference 25 numeral 1 designates a suitable casing of the usual construction formed of suitable insulating material. The casing may be formed of any desired insulating material, but I have found that a casing or shell 30 formed of turned wood not only possesses the necessary insulating qualities but, in addition, has very good acoustic qualities. The casing is provided with a cover 2, having an interiorly threaded flange 3, adapted 35 to engage external threads on the top of the casing. The cover is provided with a central opening 4.

A diaphragm 5 is arranged in the casing in the usual manner and is adapted to be 40 vibrated by the magnet. A magnet 6 is arranged in the casing and is provided with a pole piece 7 supported on a screw 8. The screw 8 passes through an opening in the bottom of the casing substantially centrally 45 thereof and is received in a threaded opening 9 in the pole piece. A rubber gasket 10 is arranged between the casing and the magnet. In place of a rubber gasket, a gasket of any other compressible material, 50 such as felt or other fibrous material, may be employed or a metallic spring may be employed. Suitable lead wires 11 are connected to the magnet in the usual manner.

In the use of the receiver, the pole piece 55 may be adjusted toward and away from the diaphragm by turning the screw in the

opening 9. With the parts in the position shown in Figure 2 of the drawings, the screw is partially removed from the opening 9 and the pole piece is arranged relatively close to the diaphragm. The gasket 10 is then expanded. To withdraw the pole piece from the diaphragm, the screw is turned into the opening 9, drawing the pole piece toward the base of the casing and placing the gasket under compression, as shown in Figure 3 of the drawings.

Heretofore adjustable receivers had been more or less expensive and by means of the present invention, I provide an adjustable 70 receiver in which the only additional parts employed are a machine screw and a rubber gasket. A further advantage of this receiver is the elimination of labor in assembling it. In the ordinary receiver, skilled 75 labor is necessary in assembling. The pole piece must be adjusted to be the same height as the rim of the telephone casing and this distance must be gauged very accurately, frequently requiring the pole piece or the 80 rim of the casing to be ground off. This necessity of accurate adjustment in assembling is eliminated by means of the present invention as the pole piece may be adjusted at any time by means of the screw 8.

It is to be understood that the form of my invention herewith shown and described is to be taken as a preferred example of the same, and that various changes in the shape, size, and arrangement of parts may be resorted to without departing from the spirit 90 of the invention or the scope of the subjoined claim.

Having thus described my invention, I 95 claim:

An adjustable telephone receiver comprising a casing formed of turned wood, a cover mounted on said casing, a diaphragm arranged in said casing adjacent said cover, a magnet arranged centrally in said casing adjacent said diaphragm, a pole piece arranged in said magnet, a disc arranged against said pole piece, a single compressible gasket arranged between said disc and said casing coaxial with said pole piece, said pole piece being provided with an axial threaded opening, and a screw extending through said casing and said gasket and received in said opening.

In testimony whereof, I affix my signature.

SIDNEY GERNSBACK.
